[57] CLAIM

The ornamental design for an amphibious aircraft, as shown and described.

DESCRIPTION

FIG. 1 is a left elevational view of an amphibious aircraft showing my new design, the right side elevational view being a mirror image of that shown;

FIG. 2 is a front elevational view thereof;

FIG. 3 is a bottom plan view thereof;

FIG. 4 is a rear elevational view thereof;

FIG. 5 is a top plan view thereof;

FIG. 6 is a left side elevational view thereof with the wing rotated parallel to the hull, the right side elevational view being a mirror image of that shown; and,

FIG. 7 is a front elevational view of FIG. 6.

Portions of the wing of FIGS. 2, 4, 5, and 6 are shown broken away to indicate indeterminate length and for convenience of illustration.

FIG. 4
